UNITED STATES PATENT OFFICE.

DUDLEY E. GALE, OF SALISBURY, MASSACHUSETTS.

JUMP-SEAT CARRIAGE.

SPECIFICATION forming part of Letters Patent No. 296,400, dated April 8, 1884.

Application filed May 14, 1883. (No model.)

To all whom it may concern:

Be it known that I, DUDLEY E. GALE, of 5
Salisbury, in the State of Massachusetts, have
invented an Improvement in Jump-Seat Car-
riages, of which the following is a specifica-
tion.

This invention relates to that class of ve-
hicles known as "jump-seat carriages;" and it
consists in the construction and combination
10 of the divers devices embodied therein, as
hereinafter more particularly and fully set
forth and claimed, my present invention be-
ing an improvement upon that shown, de-
scribed, and claimed in United States Letters
15 Patent No. 204,891, issued to me on the 18th
day of June, 1878.

In the accompanying drawings, Figure 1 is
an elevation showing the right-hand side of a
20 carriage as viewed from the left-hand of such
carriage, with the seats thereto connected by
my improved devices, said seats being both
shown as in position for use, the front and
rear portion of the body of the carriage being
25 broken away. Fig. 2 is a view like Fig. 1,
except that the rear seat is shown as jumped
forward, and the front seat is shown as turned
down beneath the rear one. Fig. 3 is a de-
tached section taken transversely to the plane
30 of the side of the body and seat, and as on
line *xx*.

In said views, *a* represents the sidesill of the
body *A*. *b* is the back or rear seat, and *c* is
the front seat, which latter is rigidly secured
upon the top of standard *d*, which is pivoted
35 at *j*. Seat *b* is connected with the body by
one or more jumping-irons, *e*, which are piv-
oted at *k* to base *e'* of the seat, and at *h''* to sill
a. A jointed standard, *f*, is pivoted by its
upper section, *f'*, at *g'*, to standard *d*, while
40 its lower section, *f''*, is pivoted at *g* to sill *a*.
A connecting-rod, *h*, is pivoted to section *f''*
at *g''*, and to *e* at *h'*, whereby when seat *b* is
jumped forward seat *c* will be turned down,
as shown in Fig. 2.

45 In my aforesaid patent the same number of
parts are employed as are herein shown; but
the arrangement and operation thereof are
unlike my present invention in this, that pivot
h'' of jumping-iron *e* is arranged above the
50 pivot *h'* of rod *h*, and is necessarily in that
part of the body shown by standard *i* in the

present drawings, while pivot *g''* was ar-
ranged in section *f''* of standard *f* above in-
stead of below pivot *g*, as I now arrange it.
Such former arrangement of parts caused se-
vere and injurious strain upon standard *i*, and,
besides, the front end of rod *h*, when entering
55 at the side of the vehicle, constituted an ob-
jectionable obstruction to the feet of the per-
son so entering. As shown in my said former
patent, the force exerted upon the connecting-
rod *h* when jumping the rear seat forward
60 was a tensile strain, while as shown in my
present drawings the force exerted upon said
rod is a pushing or compressive force, and the
65 pivots or fulcra *g* and *h''*, through which said
force is applied, are both attached directly to
sill *a*. When but one jumping-iron *e* is em-
ployed with the rear seat, the latter is some-
what liable to be turned backward by the sud-
70 den starting of the horse and throwing the
occupants off their balance; and when two
such jumping-irons are employed the wear
upon the pivot-bolts will in time allow the
75 seat a slight rising motion from the body,
which is objectionable; and to firmly lock the
seat in position when it is in either the front
or rear position, I have invented the devices
shown, which are described as follows: A flat
80 spring, *l*, is secured to base *e'* of seat *b*, either
by means of a small metallic plate, *m*, which
is secured to the base by screws, and to which
the spring is pivotally attached by rivet *n*, or
the spring may be directly secured to the base
85 by a screw. At the opposite or free end of
said spring is secured a knob, *p*, the shank of
which extends through the spring, and on it
is secured a sleeve, so as to form a stud of suf-
ficient size and length to enter a seat, *u*, formed
in standard *i* to hold the seat in position.
90 This device is of course duplicated at each
side of the seat, and its operation is both sim-
ple and effective, and will be readily under-
stood from an inspection of the drawings,
the action of the springs tending to engage
95 stud *t* in seats *u* when the seat is in either a rear
or front position for use, and the knobs *p* serv-
ing as the means by which the springs are
drawn away from the sides of the body to with-
draw studs *t* from their seats *u* when it is de-
sired to jump the seat. This device is simple
100 in form, always in position for use, easily ma-

nipulated, automatic in its engagement, and effective in its operation.

I claim as my invention—

1. The combination of body A, seats b c, standard d, jointed support f, jumping-iron e, and connecting-rod h, with said rod pivoted at its rear end to jumping-iron e at h', above pivot h'', and having its front end pivoted to section f'' of support f at g'', below pivot g, substantially as specified.

2. In combination with seat b and body A, the spring l, secured to base e' of the seat, and provided with the actuating-knob p and stud t, to engage seat u in the body, substantially as specified.

DUDLEY E. GALE.
